DISPLAY TRAY

Robert E. Brindley, New York, N.Y., assignor to Union
Carbide Corporation, a corporation of New York

Filed Oct. 8, 1968, Ser. No. 13,890

Term of patent 14 years

Int. Cl. D6—01

U.S. Cl. D80—9

FIG. 1

FIG. 2

FIG. 3

FIG. 4

FIG. 5

FIG. 6

FIG. 1 is a perspective view of a display tray showing my new design;

FIG. 2 is a top plan view thereof;

FIG. 3 is a side elevational view thereof;

FIG. 4 is a bottom plan view thereof;

FIG. 5 is an elevational view taken from one end thereof;

FIG. 6 is an elevational view taken from the end opposite that shown in FIG. 5.

The broken line representation of merchandise display cards in FIG. 1 is for purposes of illustration only.

I claim:

The ornamental design for a display tray, as shown and described.
